UNITED STATES PATENT OFFICE

2,379,967

BLOWTORCH

Homer W. Jones, Westfield, N. J., assignor to
Union Carbide and Carbon Corporation, a corporation of New York

Application July 23, 1941, Serial No. 403,636

11 Claims. (CL 158—27.4)

This invention relates to a blowtorch having an improved gas-mixing assembly which is simple and inexpensive to construct, yet insures improved mixing of the combustible and combustion-supporting gases while maintaining gas-tight joints in the blowtorch. The invention also relates to such an improved blowtorch including a simple and inexpensive disc-type gas-mixer nozzle, which may be easily removed from the blowtorch for cleaning or replacement.

It has been found desirable in blowtorches to provide double seats for the gas-mixing nozzle, one seat being adjacent to the front of the nozzle to provide a very accurately proportioned mixing gap in front of the nozzle, and the other being adjacent to the back of the nozzle to provide a seal against the escape of gas past the nozzle. Heretofore, it has been found impossible to provide such double seats without raising the cost of the nozzle prohibitively, because extremely accurate machining of all parts to close tolerances has been required to insure that the nozzle will engage both seats firmly.

The principal object of the present invention is to provide a blowtorch having a simple and inexpensive novel gas-mixing assembly provided with double seats. Another object is the provision of a blowtorch including a simple and inexpensive disc-type mixer nozzle which will cover a wide range of gas consumption for different flame adjustments, yet which may be quickly and easily removed for cleaning or replacement.

The above and other objects, and the novel features of the invention, will become apparent from the following description, having reference to the annexed drawing, wherein:

Fig. 1 is a side elevational view, partly broken away, and in longitudinal mid-section, of one form of blowtorch embodying the invention;

Fig. 2 is an enlarged longitudinal mid-sectional view of a part of the blowtorch of Fig. 1, parts being in elevation;

Figs. 3, 4, 5, and 6 are views in detail of parts of the blowtorch of Figs. 1 and 2, Figs. 4 and 6 being sectional views taken along the lines 4—4 and 6—6 in Figs. 3 and 5, respectively; and

Fig. 7 is a cross-sectional view taken along the line 7—7 in Fig. 1.

In accordance with the invention, there is provided a blowtorch having a chamber for a gas-mixing assembly, an annular shoulder adjacent to the front of the chamber forming an abutment member, and a second shoulder member spaced from the abutment member. A simple disc-shaped mixer-nozzle member in the chamber is

urged against the abutment member by a clamping member seated on the second shoulder member, and bearing against the rear end of the mixer nozzle member. Yieldable means is interposed between two of the cooperating members to take up any slack due to inequalities in machining. Preferably the yieldable means is a sharp pointed annular boss integral with one of the members, which yields to and is slightly crushed or compressed by the member cooperating therewith, thus compensating for inequalities in machining and permitting accurate seating of the two parts of the nozzle assembly against one another and against the two shoulders in the chamber to provide tight joints. Instead of an annular yieldable boss integral with one of the members of the nozzle assembly, a separate member of yieldable material may be interposed between the two cooperating members, if desired.

The invention will be described more particularly hereinafter, by way of example only, as embodied in a cutting blowtorch attachment of the medium-pressure acetylene type, which is adapted to be coupled into an ordinary welding blowpipe handle for use in cutting steel and iron. The terms "oxygen" and "acetylene" will be used hereinafter, for simplicity, to denote any suitable combustion-supporting gas and any suitable fuel gas, respectively.

As shown in the drawing, the blowtorch comprises a head member 11 connected to a rear body 12 by a tube 13 for cutting oxygen, and a tube 14 for a combustible gas mixture. A cutting tip 16, of a well-known type having a central outlet for oxygen and a plurality of outlets for a preheating combustible gas mixture surrounding the central outlet, is secured in the head member 11 by the usual coupling nut 17. A connecting nipple 18 carrying a coupling nut 19 and an adaptor disc 20, and having appropriate separate passages therein for oxygen and acetylene gases, is threaded into the rear end of the body 12 and is adapted to be coupled to a welding blowtorch handle, such as the handle of the blowtorch shown in Patent No. 2,242,471 issued May 20, 1941, to Homer W. Jones and Wilgot J. Jacobsson.

A longitudinally extending cylindrical chamber 21 in the lower portion of the rear body 12 has an annular shoulder or abutment 22 close to, but spaced slightly from, the forward end of the chamber, and a second annular shoulder 23 spaced from the shoulder 22 intermediate the ends of the chamber. An internally threaded portion 24 of the wall of the chamber 21 extends rearwardly to the rear surface of the body 12.

which is provided with a shallow counter bore 26. A relatively small diameter bore or passage 27 opens centrally from the front of the chamber 21 for conducting a combustible gas mixture to the tube 14, which is secured, as by silver soldering, within a counterbore in the front of the body 12.

A small cylindrical disc-shaped mixer nozzle 28 in the chamber 21 is seated on the annular shoulder 22 with its flat front face accurately and uniformly spaced from the front wall 29 of the chamber, forming a mixing gap 33. The nozzle 28 is provided with a central passage 31 for acetylene, and a plurality of eccentrically arranged passages 32 for gaseous oxygen arranged on an annular zone surrounding the central passage 31. The passages 32 open at their front ends into the narrow mixing gap 33 adjacent to the periphery of the latter. An annular sharp pointed boss 34, which may be of generally triangular cross section, projects rearwardly from the nozzle 28 intermediate the central passage 31 and the annular zone of the passages 32. The boss 34 provides a yieldable and easily crushable means for taking up any inequalities in the machining of the various parts of the mixing assembly, as well as providing for a gas-tight joint between the cooperating parts.

The nozzle 28 is clamped tightly in position against the abutment 22 by a clamping member 36 threaded in the chamber 21 and having a shoulder seated on the shoulder 23, thereby providing a gas-tight seal preventing the escape of gas rearwardly along the outside of the clamping member. A reduced diameter cylindrical portion 37 of the clamping member 36 extends ahead of the shoulder 23 in spaced relation to the wall of the chamber 21, and bears at its forward end against the boss 34 with a slight crushing action to provide perfect engagement between the several cooperating surfaces. An annular laterally projecting flange 38 adjacent to the forward end of the clamping member 36 extends toward the wall of the chamber 21, but is spaced therefrom, to provide a baffle for insuring uniform distribution of gas to the several passages 32 of the mixer nozzle 28. A central passage 39 in the clamping member 36 is aligned with the central passage 31 in the mixer nozzle 28 for conducting acetylene thereto. A slot 41 in the rear end of the clamping member 36 permits easy removal of the latter from the chamber 21 by a screw-driver.

The rear end of the chamber 21 is plugged by a closure comprising an externally threaded plug 42 threaded into the rear end of the chamber. A shoulder 43 intermediate the ends of the plug 42 is seated firmly against the rear face of the body 12 within the counterbore 26 to provide a seal against the leakage of gas to the atmosphere from the chamber 21. At its inner end, the plug 42 terminates a substantial distance in back of the rear end of the clamping member 36, thus providing a space 44 in back of the clamping member for the introduction of gaseous acetylene into the chamber 21.

The mixer nozzle 28 and the clamping screw 36 are desirably made of bronze, the sharp pointed boss 34 yielding under pressure satisfactorily even though it has the same hardness as the clamping screw. Sometimes, however, the mixer nozzle 28 may be made of metal softer than the clamping screw 36, if easier crushing of the boss 34 is desired. It is also apparent that the yieldable boss may be provided on the front of the clamping screw 36 instead of on the nozzle 28. When the

annular sharp-edged boss is made of a material having a greater hardness than that of the member bearing thereon, it is evident that the boss will form an indentation in the softer metal, thereby compensating for inaccuracies in machining as though the boss itself had been crushed or compressed. Also, the boss member 34 may be constructed of a metal having greater or lesser hardness than the base metal of the nozzle and welded or otherwise secured thereto.

In the operation of the blowtorch, acetylene from a central passage 46 in the nipple 18 is conducted by way of a passage 47 in the body 12 directly to the space 44, from whence it passes through the central passages 39 and 31 in the clamping member 36 and the nozzle 28, respectively, and is discharged centrally into the mixing gap 33 at the front of the nozzle.

Gaseous oxygen from the eccentrically arranged passages 48 in the connecting nipple 18 is discharged into a cavity 49 in the rear end of the body 12, from whence it is conducted by way of a passage 51 to a valve chamber 52, containing a valve 53 operable by a lever 54 for controlling the admission of cutting oxygen to the tube 13. A second oxygen passage 56 in the body 12 (see Fig. 7) takes off from the intake side of the valve chamber 52 for conducting gaseous oxygen to the second valve chamber 57 containing a needle valve 58 controlling the admission of gaseous oxygen to the chamber 21. From the valve chamber 57, a short passage 59 leads to the chamber 21 on the side of the baffle 38 remote from the nozzle 28, for discharging the gaseous oxygen into the annular space surrounding the annular boss 34 and the forwardly projecting portion 37 of the clamping screw 36. The gaseous oxygen from the chamber 21 then is uniformly distributed to the several passages 32 in the mixer nozzle 28, and is discharged into the narrow mixing gap 33 at the front of the nozzle adjacent to the periphery of the gap. The gaseous oxygen flows inwardly in the gap 33 perpendicularly to the central stream of acetylene from all sides thereof and mixes intimately therewith. The combustible gas mixture becomes more completely mixed during its passage through the passage 27 and the tube 14 to the head 11, from which it is delivered to the tip 16 to provide a preheating flame.

The mixing assembly may be removed from the blowtorch for cleaning or replacement simply by removing the closure plug 42 and unthreading the clamping member 36 from the chamber 21, after which the mixer nozzle 28 may be dropped from the chamber.

A specific embodiment of the present invention has been described by way of example only, and scope of the invention is not to be limited to the specific embodiment described because changes in construction and arrangement within the spirit of the invention may be made by those skilled in the art.

What is claimed is:

- 65 1. A blowtorch having a chamber; an abutment member in said chamber; a shoulder member spaced from said abutment member; a mixer nozzle member seated on said abutment member; and a clamping member gas-tightly seated on said shoulder member and gas-tightly seated also on said mixer nozzle member; one of said members including a yieldable boss integral therewith, and the member seated on said last-named member bearing against said boss with a slight compressing action, thereby providing for accurate

seating of each member against the member cooperating therewith.

2. A blowtorch having a chamber; an abutment in said chamber; an annular shoulder spaced from said abutment; a mixer nozzle member in said chamber abutting against said abutment; a clamping member in said chamber gas-tightly engaging said mixer nozzle member, said clamping member also gas-tightly engaging said annular shoulder; and one of said members having a yieldable boss integral therewith; the other of said members bearing against said boss with a slight compressing action, thereby providing for accurate seating of said clamping member on said shoulder.

3. A blowtorch having a chamber; an abutment in said chamber; an annular shoulder spaced from said abutment; a mixer nozzle in said chamber abutting at one end thereof against said abutment, said mixer nozzle having an annular yieldable boss projecting from the opposite end thereof; and a clamping member in said chamber gas-tightly engaging said annular shoulder, said clamping member bearing against said boss with a slight compressing action, thereby providing a gas-tight joint between said mixer nozzle and said clamping member, and providing for accurate seating of said clamping member on said shoulder.

4. A blowtorch having a chamber; a gas-mixture passage leading from said chamber; an abutment adjacent to one end of said chamber; an annular shoulder spaced from said abutment; a mixer nozzle in said chamber abutting against said abutment, said nozzle having a central first-gas passage, and a plurality of second-gas passages arranged on a zone surrounding said central passage, said mixer nozzle also having a sharp pointed yieldable annular boss projecting rearwardly between said central passage and said zone; a clamping member in said chamber bearing against said boss with a slight compressing action and forming a seal between said central passage and said second-gas passages, said clamping member also accurately engaging said annular shoulder in gas-tight relationship thereto, and said clamping member having a passage; an annular space surrounding said boss for distributing gas to said second-gas passages; a passage for introducing a first-gas into the passage in said clamping member; and a passage for introducing a second-gas into said annular space.

5. A blowtorch comprising a body having a chamber extending inwardly from one surface thereof, said chamber having a wall; a gas mixture passage leading from said chamber; an abutment in said chamber; an annular shoulder spaced from said abutment; a mixer nozzle member abutting against said abutment, said mixer nozzle member having separate passages therethrough; a clamping member in said chamber gas-tightly engaging both said annular shoulder and said mixer nozzle member, said clamping member having a passage; one of said members including an annular yieldable boss spaced from said wall, the other of said members bearing against said boss with a slight compressing action to provide a gas-tight seal between said separate passages, and to provide accurate seating of said clamping member on said shoulder; a closure in said chamber in spaced relation to said clamping member; and separate passages in said body for supplying gases to the space between said annular boss and said wall, and to the space between said clamping means and said closure.

6. A blowtorch having a chamber; a gas-mixture passage leading from said chamber; an abutment adjacent to one end of said chamber; an annular shoulder spaced from said abutment; a mixer nozzle member in said chamber abutting against said abutment, said nozzle member having a central first-gas passage, and a plurality of second-gas passages arranged on a zone surrounding said central passage; a clamping member in said chamber gas-tightly engaging both said annular shoulder and said mixer nozzle member, said clamping member having a passage and comprising a portion extending ahead of said annular shoulder in spaced relation to the wall of said chamber, providing an annular space; one of said members including an annular yieldable boss integral therewith, the other of said members bearing against said boss with a slight compressing action to provide a gas-tight seal preventing gas leakage between said annular space and said central passage, and to provide for accurate seating of said clamping member on said shoulder; a passage for introducing a first-gas into the passage in said clamping member; and a passage for introducing a second-gas into said annular space.

7. A blowtorch as claimed in claim 6 wherein the portion of said clamping member ahead of said shoulder includes an annular baffle projecting toward the wall of said chamber, and wherein in the passage for introducing said second-gas into said annular space opens into the latter on the side of said baffle remote from said mixer member.

8. In combination, a body having a chamber; an abutment in said chamber; a shoulder spaced from said abutment; a first member in said chamber abutting at one end against said abutment, said first member having an annular sharp-edged yieldable boss projecting from the other end thereof; and a second member in said chamber engaging both said shoulder and said first member, said second member bearing against said boss with a slight compressing action to provide a tight joint therebetween, and to provide accurate seating of said second member on said shoulder.

9. A blowtorch having a body provided with a chamber having a wall, said chamber having an entrance in one surface of said body; mixer nozzle means in said chamber; means cooperating with said mixer nozzle means for spacing the latter from the end of said chamber remote from said entrance; clamping means threaded to the wall of said chamber and engaging said mixer nozzle means; and shoulder means in said chamber facing toward said entrance and cooperating with said clamping means to provide a seal against the flow of gas around said clamping means; one of said means including deformable material adapted to yield slightly under the pressure of the means cooperating therewith, whereby said clamping means accurately engages both said shoulder means and said mixer nozzle means.

10. A blowtorch having a body provided with a chamber having a wall, said chamber having an entrance in one surface of said body; a first shoulder in said chamber near the end thereof remote from said entrance, and facing toward the latter; a second shoulder in said chamber between said first shoulder and said entrance, and facing toward the latter; a mixer nozzle member in said chamber seated on said first shoulder; and a clamping member in said chamber threaded to the wall thereof and seated on said second

shoulder to provide a seal against the flow of gas around said clamping member, said clamping member also engaging said mixer nozzle member; one of said members including a portion of deformable material adapted to yield slightly under the pressure of the other of said members, whereby said clamping member accurately engages both said second shoulder and said nozzle member.

11. A blowtorch having a chamber; an abutment member in said chamber; an annular shoulder member spaced from said abutment member; a mixer nozzle member in said chamber seated on

said abutment member; and a clamping member in said chamber gas-tightly seated on both said shoulder member and said mixer nozzle member and holding the latter against said abutment member; a first one of said members including a sharp pointed annular boss integral therewith bearing against a second one of said members, one of said first and second members yielding slightly under the pressure of the other of said first and second members, whereby said clamping member accurately seats on both said shoulder member and said mixer nozzle member.

HOMER W. JONES.
